(57) **CLAIM**

The ornamental design for an electronic device, as shown and described.

DESCRIPTION

FIG. 1 is a top perspective view of a first embodiment of an electronic device;

FIG. 2 is a bottom perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof;

FIG. 8 is a bottom view thereof;

FIG. 9 is a top perspective view of a second embodiment of an electronic device;

FIG. 10 is a bottom perspective view thereof;

FIG. 11 is a front view thereof;

FIG. 12 is a back view thereof;

FIG. 13 is a right-side view thereof;

FIG. 14 is a left-side view thereof;

FIG. 15 is a top view thereof;

FIG. 16 is a bottom view thereof;

FIG. 17 is a top perspective view of a third embodiment of an electronic device;

FIG. 18 is a bottom perspective view thereof;

FIG. 19 is a front view thereof;

FIG. 20 is a back view thereof;

FIG. 21 is a right-side view thereof;

FIG. 22 is a left-side view thereof;

FIG. 23 is a top view thereof;

FIG. 24 is a bottom view thereof;

FIG. 25 is a top perspective view of a fourth embodiment of an electronic device. The stippled portions of the fourth embodiment represent textured portions of the electronic device. The line shading shown on the sides and top front edge of the fourth embodiment represents high gloss surfaces of the electronic device;

FIG. 26 is a bottom perspective view thereof;

FIG. 27 is a front view thereof;

FIG. 28 is a back view thereof;

(Continued)

FIG. 29 is a right-side view thereof;
 FIG. 30 is a left-side view thereof;
 FIG. 31 is a top view thereof; and,
 FIG. 32 is a bottom view thereof.
 The broken lines depict portions of the electronic device that
 form no part of the embodiment in which they are shown.
